ATTORNEYS

UNITED STATES PATENT OFFICE.

ADOLPH VON SCHADE, OF NEWPORT, RHODE ISLAND.

BOTTLE-WASHER.

SPECIFICATION forming part of Letters Patent No. 241,834, dated May 24, 1881.

Application filed April 13, 1881. (No model.)

To all whom it may concern:

Be it known that I, ADOLPH VON SCHADE, of Newport, in the county of Newport and State of Rhode Island, have invented certain new and useful Improvements in Machines for Washing and Cleaning Bottles; and I do hereby declare that the following is a full, clear, and exact description of the invention, which will enable others skilled in the art to which it appertains to make and use the same, reference being had to the accompanying drawings, which form a part of this specification.

Figure 1 is a front view. Fig. 2 is a side view. Fig. 3 is a vertical sectional view of the upper end of the revolving brush and adjoining parts. Fig. 4 is a vertical sectional view of the lower end of the brush-tube and adjoining parts; and Fig. 5 is a sectional view on the line α α , Fig. 3.

Corresponding parts in the several figures are denoted by like letters of reference.

This invention relates to machines for washing and cleaning bottles; and it consists in certain improvements in the construction of the same, which will be hereinafter fully described, and particularly pointed out in the claims.

In the drawings hereto annexed, A represents a table or platform, supported upon legs B, and having a central vertical opening, above which is arranged a metallic casing, C, containing a suitably-constructed hydraulic or other motor, to the construction of which, however, no claim is herein made, and which is therefore not shown in the drawings. It embodies in its construction a horizontal rotary wheel or body, D, having a vertical tubular shaft, E, the upper end of which is slightly beveled or spread outward, as shown at F. At one end the shaft E is provided with a collar, G, having a set-screw, H, which works in a vertical longitudinal slot 35 or groove, I, in a tube, J; sliding vertically in the tubular shaft E, and being connected to the latter by the set-screw H it revolves therewith when in motion. The tube J is threaded at its upper end to receive the threaded and longitudinally-perforated head K of the brush L, which is preferably made of bristles.

To the sides of head K are attached several bent springs, M, provided at their upper ends with auxiliary brushes N.

50 The lower end of tube J is connected, by a swivel-joint, O, with a knee-joint or tube, P,

in which a stop-cock, Q, is fitted, as shown. Said stop-cock is operated by a bell-crank lever, R, having at the end of one of its arms a weight, S, which operates to open the flow of water from a flexible tube, T, connected to the knee-joint, as shown. To the other arm of lever R is attached a cord or chain, U, the other end of which is attached to the under side of the table or platform. A weight, V, is hooked or otherwise secured to the under side of the knee-joint, so as to force the latter and the tube J in a downward direction.

The swivel-joint O is mounted in a frame, W, consisting essentially of a bent rod sliding vertically in a suitable bearing of the table or platform, and provided at the end of its horizontal arm with a sleeve, X, sliding upon a vertical guide-rod, Y, secured under the table.

To the upper end of the vertical arm of frame W is attached a cord or chain, Z, passing over a pulley, A', and having its other end attached to a lever, B', which may be operated by hand or foot, according to its location.

If the motor is a hydraulic one, water may be admitted to the casing by a tube, C', as shown. The casing is also provided with a spout, D', for the escape of waste water. At the upper end of the casing is formed a flange, E', to receive the neck of bottles which are to be cleaned.

In operation the bottle is inverted and adjusted within the flange E'. By operating the lever B' the frame W is now raised, carrying with it the revolving brush-tube J until the brush reaches the bottom of the inverted bottle. At the same time the weight S opens the stop-cock Q and starts the flow of water through the tube J and the perforated brush-head into the bottle, which is thus thoroughly scoured and rinsed. When the lever B' is released the weight V serves to return the parts to their original position, the cord U being thus straightened, so as to operate the bell-crank lever and cut off the flow of water, waste of which is thus prevented. When the frame W, with the operating parts, is lowered the brush-head K partly enters the upper beveled end of the tubular shaft E, thus compressing the springs carrying the auxiliary brushes, so that the next bottle to be cleaned may be readily adjusted over the latter.

This machine is simple, convenient, effective,

and easily operated, and it may be manufactured at a comparatively small expense.

Having thus described my invention, I claim and desire to secure by Letters Patent of the

United States—

1. In a machine for washing bottles, the combination, with a suitable motor having a vertical tubular shaft, E, provided with a set-screw, H, and beveled or spread upper end, F, of the vertically-sliding tube J, having slot I, and perforated brush-head K, having springs M, provided with auxiliary brushes N, substantially as herein described, for the purpose set forth.
2. In a machine for cleaning bottles, the combination, with a vertically-sliding rotating brush-tube, of a swiveled knee-joint having a

stop-cock for the admission of water, and suitable operating mechanism, as herein described, for the purpose set forth.

3. The combination, in a machine for cleaning bottles, of the rotating vertically-adjustable brush-tube, the swiveled knee-joint P, having stop-cock Q, and weighted bell-crank lever R, cord U, weight V, frame W, and mechanism for raising or lifting the latter, as herein described, for the purpose shown and specified.

In testimony that I claim the foregoing as my own I have hereto affixed my signature in presence of two witnesses.

ADOLPH VON SCHADE.

Witnesses:

ALBERT VON HOFEN,

PATRICK J. GALVIN.
